(57) **CLAIM**

The ornamental design for a container and closure, as shown and described.

DESCRIPTION

FIG. 1 is a perspective view of the container and closure of my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken line showing of the bottom of the container is for illustrative purposes only and forms no part of the claimed design.

1 Claim, 6 Drawing SheetsFIG. 1

FIG. 2

FIG. 3

FIG. 4

FIG. 5

FIG. 6

FIG. 7
